PLANT HOLDER

Thomas H. Davis, Brooklyn, N. Y., assignor to Buck Enterprises, Inc., Brooklyn, N. Y., a corporation of New York

Application September 21, 1955, Serial No. 38,018

Term of patent 14 years

(Cl. D35—3)

Fig. 1 is a top plan view of a plant holder embodying my novel design;

Fig. 2 is a front view thereof; and

Fig. 3 is a side view thereof.

I claim:

The ornamental design for a plant holder, as shown.
